UNITED STATES PATENT OFFICE.

JOHN GEORGE AULSEBROOK KITCHEN, OF SCOTFORTH, LANCASTER, ENGLAND,
ASSIGNOR OF ONE-HALF TO GORDON HENRY FRASER, OF LIVERPOOL, ENGLAND,
AND JAMES RYDER O'HANLON, OF WESTWOLD, BLUNDELLSANDS, ENGLAND.

RUDDER-OPERATING GEAR.

1,371,492.

Specification of Letters Patent. Patented Mar. 15, 1921.

Application filed August 9, 1920. Serial No. 402,205.

To all whom it may concern:

Be it known that I, JOHN GEORGE AULSEBROOK KITCHEN, a subject of the King of Great Britain and Ireland, and resident of 5 Rose Bank, Scotforth, Lancaster, in the county of Lancaster, England, have invented certain new and useful Improvements Relating to Rudder-Operating Gears, of which the following is a specification.

10 This invention relates to the operating gear for rudders of the type which are arranged in pairs at the opposite sides of the screw propeller or propellers and adapted for both boat steering and reversing purposes as set forth in prior U. S. Patent No. 1186210.

The object of the present invention is to provide an improved compact arrangement of the gear which shall insure that the 20 rudders are maintained in their closed or boat reversing position while the boat is being steered when going astern.

Referring to the two accompanying sheets of explanatory drawings:—

25 Figure 1 is a sectional side elevation, Fig. 2 a plan, and Fig. 3 a sectional end elevation representing one form of rudder operating gear constructed in accordance with this invention.

30 Fig. 4 is a sectional side elevation, Fig. 5 a plan and Fig. 6 an end view of another form of the said gear.

Fig. 7 is a diagrammatic plan view showing the rudders in the closed or boat reversing position.

The same reference letters in the different views indicate the same or similar parts.

In accordance with my present invention the tiller or tiller arm or bar *a* fulcrums 40 about the axis of the concentric rudder stocks; preferably it is fulcrumed freely upon the end of the inner stock *b* of the two concentric rudder stocks *b* and *c*. The said arm or bar *a* has a sliding collar *d* thereon which is connected by links *e* to arms or levers *f* upon the rudder stocks. The said collar can move freely along the tiller *a*. The arms or levers *f* aforesaid are also connected by means of rods *g*, to a 45 cross-head or like part *h* fulcrumed about a pin *i*, which in the example illustrated at Figs. 1, 2 and 3, can be moved away from or toward the axis of the rudder stocks by

a screw *j* and sliding nut device *k*, the screw, on its rotation by a sprocket or chain wheel 55 as *l*, effecting the said movements of such nut or slide *k* with which the fulcrum or pin *i* is formed. The said cross head *h* is so shaped that when the arms or levers *f* upon the rudder stocks are in the "rudder 60 closed" or "boat reversing" position, the said arms or levers are parallel with the parts of the cross head *h* on the respective sides of the cross head fulcrum. Such closed position of the rudders *m* is shown in the 65 diagrammatic view at Fig. 7; the said view shows also the arms *f* of the rudder stocks, the cross head *h* and the aforesaid connecting rods *g*. It follows therefore that when the rudders are closed, any movement given to 70 the arms or levers *f* and so to the cross head, by the turning of the tiller about the rudder stocks for boat steering purposes, will not cause any relative movement of the rudders in opposite angular directions such 75 as would occur if the said cross head and arms or levers were not parallel, as before described, when the rudders were closed together for reversing.

In some cases, of which an example is 80 given at Figs. 4, 5 and 6, we may operate the cross head fulcrum *i* by means of a reciprocating part *k* actuated by a crank pin *n*, the position of the said pin when the rudders are closed for boat reversing purposes being approximately in, or at only a 85 slight angle to, a line passing through the axis of the crank *o* and the axis of the fulcrum pin *i*. By this means we are enabled to effect the final closing movement of the 90 rudders with very considerable leverage or mechanical advantage due to the toggle action of the connecting rod or link *p* between the crank pin *n* and the fulcrum pin *i* of the cross head *h*. As shown at Figs. 4 and 95 5, the arms or levers *f* of the rudder stocks are in the positions corresponding to the fully open or approximately fully open position of the rudders. It will be understood that if the crank pin *n* has moved through 100 a semi-circle from the position shown at Fig. 4, it will have brought the said arms *f* to the rudder closed or boat reversing position shown at Fig. 7, and that the connecting rod *p* will then be at the same obliquity 105 or angularity as that shown at Fig. 4, so that

the crank pin *n* will be enabled to exert the desired toggle action for the purpose aforesaid.

The crank *o* is rotated through the medium of a chain or sprocket wheel as *l* or otherwise.

The tiller bar *a* may be actuated directly by hand or through suitable transmission means.

10 Having now described my invention what I claim as new and desire to secure by Letters Patent is:—

1. In operating gear for rudders adapted both for boat steering and reversing purposes, the combination comprising two rudders with rudder stocks, arms upon the rudder stocks, a pivotally mounted cross head and rods connecting same with said arms, a tiller, and means whereby the rudders are 15 maintained in their closed or boat reversing position while the vessel is being steered when going astern, as set forth.

2. In rudder operating gear having means whereby the rudders are maintained in their 25 closed or boat reversing position, while the vessel is being steered when going astern, the combination with the tiller and the rudder stock arms or levers, of a collar carried by and free to slide on said tiller, and links connecting the rudder stock arms and 30 said collar, as set forth.

3. In rudder operating gear, having means whereby the rudders are maintained in their closed or boat reversing position, 35 while the vessel is being steered when going astern, the combination with a tiller, a piv-

otally mounted cross head, and rudder stock arms or levers, of a collar carried by and free to slide on said tiller, means connecting the rudder stock arms or levers with 40 the said cross head and with the said collar, and means for reciprocating the cross head, as set forth.

4. In rudder operating gear, having 45 means whereby the rudders are maintained in their closed or boat reversing position, while the vessel is being steered when going astern, the combination with a tiller, a pivotally mounted cross head, and rudder stock arms or levers, of a collar carried by 50 and free to slide on said tiller, means connecting the rudder stock arms or levers with the said cross head and with the said collar, means for reciprocating the cross head and for imposing a toggle action thereon, 55 as set forth.

5. In operating gear for rudders adapted both for boat steering and reversing purposes the combination with a tiller, a pivotally mounted cross head, and rudder stock arms or levers, of a collar carried by 60 and free to slide on said tiller, means connecting the rudder stock arms with the said collar, and means whereby the said cross head is kept in parallel with the said rudder stock arms while the latter are 65 moved by the tiller for steering when the vessel is going astern, as set forth.

In testimony whereof I have signed my name to this specification.

JOHN GEORGE AULSEBROOK KITCHEN.
